UNITED STATES PATENT OFFICE.

JOHN STEWART SMITH AND SAMUEL SMITH, OF GLASGOW, COUNTY OF LANARK, SCOTLAND.

JACQUARD MACHINE FOR LOOMS.

SPECIFICATION forming part of Letters Patent No. 380,462, dated April 3, 1883.

Application filed November 20, 1886. Serial No. 219,445. (No model.)

To all whom it may concern:

Be it known that we, JOHN STEWART SMITH and SAMUEL SMITH, of Glasgow, county of Lanark, Scotland, have invented an Improvement 5 in Jacquard Machines for Looms, of which the following is a specification.

Our invention has reference to Jacquard machines for looms; and it consists of certain improvements in the construction thereof, all of 10 which are fully set forth in the following specification, and shown in the accompanying drawings, which form part thereof.

By our invention we impart a smooth rotary motion to the power-applying devices of Jacquard machines, which will enable the loom to 15 work without shaking and to be driven much faster.

In the ordinary jacquard the motion by which are raised the brander-knives or the trap-board 20 or hook lifting and lowering frame (which acts upon the harness-threads) is invariably communicated by levers working from above by lifting or from under by thrusting upward. This motion causes an overbalancing strain and 25 gives a jerky and shaky motion to the loom.

In our invention a shaft is placed in the middle of the jacquard, preferably near the bottom and under where the needles operated upon by the loom-pattern cards would come, and 30 on which shaft we secure six eccentrics, cranks, or cams—two on the inside of the frame of the machine to lift and lower the trap-board which catches the usual knotted tails, two outside of the frames to lower and lift the top board from 35 which are suspended the knotted tails, and two outside of these again to work the card barrel or cylinder.

By using the two sets of eccentrics or cams, as described, and causing the trap-board to rise 40 with the knotted tails (which have been acted upon by the needles and pattern-cards in the usual way) simultaneously with the lowering of the top board and the remainder of the tails and harness-threads controlled thereby, the 45 open shed can be obtained by much smaller eccentrics and the warp-yarn only requires to pass through half the distance. At same time the weight on the descending board acts as a counterpoise to the weight on the rising board, 50 (or vice versa,) thereby helping the working of the loom and inducing a more uniform and

smooth action; but it is not essential that both boards should move. Either may be a fixture and only one move.

This improvement applies equally to Jacquard machines either with trap-board and knotted tails, as described, or with brander-knives and hooked wires, as said boards and brander or hook-lifting knives are substantially the same elements, both operating for the same 55 purpose, and the before considered as equivalents.

In the drawings, Figure 1 is a side elevation of a Jacquard machine embodying our invention. Fig. 2 is a sectional elevation of same 60 on line *xx* of Fig. 3, and Fig. 3 is a front view of same.

A are side frames of the machine, which are connected by braces *a*.

B is a horizontal shaft extending across the 70 machine, which is adapted to be driven in any manner from the loom or power mechanism for driving the same. This shaft may be located in any convenient position on the frame. Upon this shaft, within the frames A, are secured eccentrics or cams *c*, and upon the outside of the 75 said frames, and also secured to the shaft, are the eccentrics *d* and *e*. These eccentrics are preferably arranged at angles of ninety degrees with reference to each other.

C is the trap-board, which is supported upon vertical slides *H*, having guides *h*, adapted to slide in the vertical grooves *F* on the frames A, and said slides are moved vertically by the two eccentrics *c*, upon which they directly rest.

D is the top board, which is connected by guides *g* (working in the guide-slots *F* on the frames A) with the vertical slides *G*, which receive motion from the cams or eccentrics *d*, and upon which they directly rest. The top 90 board or lifting-frame, *D*, is, for simplicity's sake, shown as a simple plain board; but it is evident that so far as our invention is concerned it might be constructed like any of the well-known hook-lifting frames or griffs 95 and provided with the usual blades or knives. (Indicated in dotted lines, Fig. 2.) These details are of little moment, so far as the invention is concerned, as the top board and the hook-lifting frame or griff are equivalents and 100 interchangeable, and the other one might be employed without in the least changing the

function of the operating-cams and their connections. It will be noted that the eccentrics *d* and *e* are arranged diametrically opposite, so that the trap-board and the top board approach and recede from each other. It is evident that either set of these eccentrics may be dispensed with and the corresponding board, D or C, allowed to be stationary. In some cases the trap-board (or where hooks are employed the lower griff) may be made stationary, while the top board, D, or griff may be raised or lowered by the eccentrics in the manner described. On the other hand, the top board, D, or griff may in some looms be made stationary, while the trap-board C or lower griff may be raised and lowered by the eccentrics in the manner described. It is obvious that the latter arrangement involves merely a slight reversal of that first referred to, and practically may be regarded as the equivalent thereof.

25 E is the card-cylinder, which is supported by reciprocating horizontal rods I, working in bearings *i*. Said rods are provided with arms J J, between which the eccentrics or cams *e* work to cause a reciprocation of said card-cylinder.

30 The weight of the trap-board or top board and their slides always insures them working with a steady surface contact with their eccentrics, and the arms J may be adjusted upon their rods by set-screws *j*, so as to avoid all lost motion with reference to the eccentrics *e*. By this construction it is seen that a most constant and uniform movement of parts is obtained, all lost motion prevented, less power required, and when applied being uniformly distributed over the entire series of movements. This perfect action of the jacquard enables a 35 greater speed of the operation in the loom, and thereby increases its product in a given time. While we prefer to use eccentrics with the slides resting directly upon them, yet it is evident that an eccentric-strap may encircle the

eccentric and be pivoted to the guides of the 45 boards C and D, as indicated in dotted lines in Fig. 1, in which case we have in effect a simple crank and connecting-rod in which the crank is the diameter of the eccentric, cranks and eccentrics being identical in operation and principle, and therefore equivalents. It is also evident that the exact configuration of the cams might be varied, though we prefer to use true eccentrics.

50 While we prefer the construction shown, we do not limit ourselves to the details thereof, as they may be modified without departing from our invention.

Having now described our invention, what we claim as new, and desire to secure by Letters Patent, is—

1. In a Jacquard machine, the combination of the main frame and the vertically-reciprocating top and trap boards, adapted to approach toward each other or recede from each other, 65 with a rotating shaft and eccentrics to simultaneously lower the top board and raise the trap-board, or vice versa, substantially as shown and described.

2. The combination, with the vertically-reciprocating top and trap boards or griffs, the card-cylinder, the guide-rods I, and arms J, of the shaft B and the eccentrics thereon, adapted, as described, to lower the top boards or griffs and raise the trap-board or griff, and vice versa, and reciprocate the card-cylinder, 75 substantially as described.

3. The combination, with the top board, the card-cylinder, the guide-rods I, and arms J, of the eccentrics *e* *d* and shaft B, substantially as 80 described.

In testimony of which invention we hereunto set our hands.

JOHN STEWART SMITH.
SAMUEL SMITH.
